UNITED STATES PATENT OFFICE.

JOHN RECKER, OF NEWARK, NEW JERSEY.

KEYLESS LOCK.

Application filed September 10, 1927. Serial No. 218,651.

This invention relates to locks and more particularly to types variously known as keyless or permutation, with special reference to such locks as are applied to brief cases, 5 satchels, trunks and like containers.

One of the objects of the present invention is to provide a lock in which a keeper is adjustably received at different points within the lock casing, the locking bolt being yield- 10 able to permit engagement of the keeper when entered under moderate pressure.

It is a further feature to provide a lock which is substantially secure against intrusion, operable only by persons knowing the 15 combination, the characters of which appear on the several dials controlling the unlocking elements.

Another aim is to produce a neat and attractive lock composed of few and simple parts all 20 readily amenable to economical and rapid production by ordinary methods.

These objects and others of like nature are attained by the novel design, construction and combination of parts hereinafter described, 25 and shown in the accompanying drawing, forming a material part of this disclosure, and in which:—

Figure 1 is a front elevational view of an embodiment of the lock, parts being broken 30 away in order to disclose the construction.

Figure 2 is a longitudinal sectional view taken on line 2—2 of Figure 1.

Figure 3 is a plan view of the lock casing, looking from the inner side and showing two 35 of the control members engaged therein.

Figure 4 is a top plan view of the slidable bolt plate indicating the third or central control device as carried by it.

Figure 5 is a plan view of the cover or base 40 plate, looking from the inner side thereof.

Throughout the several views the numeral 10 designates in general one of the body walls of the container and 11 the cover therefor.

Secured to the cover 11 is a keeper plate 12 45 firmly held by rivets 13, the end of the keeper, adjacent the lock, being inturned at a right angle to produce a looped element 14 quite of the ordinary type.

The lock is composed of a sheet metal casing 50 15, which may be made in any preferred pro-

file, and is provided with a circumambient flanged edge 16 forming the side walls of the casing and adapted to make intimate contact with the body wall 10, as best seen in Figure 2.

The rectangular portion of the lock casing 55 face, adjacent the keeper, is provided with a plurality of spaced transverse openings 17, and at the opposite end is a relatively short longitudinal slot 18.

The base of the casing consists of a metal 60 plate 20, containing transverse slots 21 in register with the slots 17 and a sheared opening 22 to produce an inturned transverse lug 23, the purpose of which will hereafter 65 become apparent.

Also in the narrow end of the plate 20 is a similar sheared opening 24, the metal being shaped to produce a shorter, indent lug 25.

The base is connected to the front wall of the casing by rivets 26, passing through appropriate openings in the offset portions 27 and 28 of the base and furthermore, the plate 20 is bent to present lateral elements 29, level with the surface of the offset portion 30, and from these elements extend lugs 31 adapted 75 to be passed through the material of the container and bent thereover, forming a secure fastening means in a simple manner.

Slidable intermediate the inner surface 15 of the casing and adjacent surface of the 80 plate 20, is a sliding bolt plate 32 having a recessed outer end 33 and containing openings 34 into each of which project loop engaging elements 35, bevelled on their outer surfaces so 85 that when the keeper element 14 is pressed thereagainst as to yield and permit the keeper to enter.

The remote end of the bolt plate contains a rectangular recess 36, beyond which is an opening 37 sheared to produce a lug 38 positioned in register with the corresponding lug 23 of the casing base.

Both lateral edges of the bolt 32 are extended midway their length to form wing elements 39 having narrow projections 40, the 95 bolt plate thereafter being contracted as best seen in Figure 4.

Rotatably mounted in the widest portion of the casing element 15 are a pair of spaced registering studs 42 having fixed on their 100

outer extending ends knurled knobs 43, each bearing a circular row of characters 44, as the numerals shown.

Rigidly fixed to the inner extending ends 5 of the studs 42 are discs 45, each containing a single notch 46 adapted, when in register, to receive the lugs 40 of the locking bolt but at all other times the ends of the lugs may ride against the peripheries of the discs and prevent unlocking of the container.

The position of the discs are readily ascertained by comparison of the predetermined numerals with lines 47 on the face of the casing, the dials being actuated in a manner well understood.

Disposed between the lugs 23 and 38, respectively of the base and bolt, is a bent flat spring 48 obviously operating to yieldably press the bolt plate towards the keeper and into an engaging position.

The bolt plate is normally retracted by another knurled knob 50 bearing characters 51 upon its face, each of which is registerable with the indented mark 52 on the casing; 25 this knob is fixed on a stud 53 rotatably mounted on the inner portion of the bolt plate 32, the stud being freely slideable in the slot 18 of the casing and has secured at its inner end a disc 54 containing a single recess 55, receptive of the lug 25 formed near the end of the base plate 20.

From the foregoing it will be seen that when the character bearing knobs 43 and 50 are rotated into the position shown in Figure 35 1, the discs 45 carried by them will be turned to cause their notches 46 to register with the lugs 40 of the locking bolt and enter therein when the knob 50 has been turned to present the recess 55 in the disc 54, and the knob 50 40 drawn down, carrying with it the bolt plate 32 and releasing the keeper and so long as the several knobs remain in that position it will be possible to enter the keeper loop without difficulty, the spring permitting the lock bolt 45 to yield in so doing.

However when the bolt plate is in an advanced or locking position and any one of the three discs is rotated into another position from that shown, the bolt plate is held 50 rigidly, retaining the keeper, which may have been selectively entered in any of the several openings 17, locking the container in an efficient manner.

As changes of construction could be made 55 within the scope of the invention, it is intended that all matter contained in the foregoing description or shown in the accompanying drawings shall be interpreted as illustrative and not in a limiting sense.

Having thus described my invention, what 60 I claim as new and desire to secure by Letters Patent, is:—

1. A lock comprising a casing having a plurality of transverse openings in its face, 65 a keeper having a loop to pass selectively into

the openings, a bolt plate slideable in said casing to engage the keeper, a lug raised from said casing, a second lug on the back of said plate, a spring disposed between said lugs urging the bolt plate into engagement, a lug 70 on the base of said casing to extend therein, rotatable means slideable on the face of said casing and operably fixed in said bolt plate to convey lineal motion thereto, said means including a slotted disc receptive of said base lug when in a predetermined position to permit movement of the bolt plate and prevent movement when in any other position and auxiliary means in said casing to control the movement of said slide.

2. A lock comprising a casing having a plurality of transverse openings in its face, a keeper having a loop to pass selectively into the openings, a bolt plate slideable in said casing to engage the keeper, yieldable means 80 to project said bolt plate into engagement therewith, a character bearing knob slideable on said casing and rotatable in said bolt plate whereby it may be manually retracted, means associated therewith to prevent retraction except said knob be in a predetermined position denoted by the characters thereon and means in each side of said casing adjustable to engage and disengage said bolt plate to control its movement.

3. A lock comprising a casing having one or more transverse and longitudinal slots in its face, a keeper engageable selectively in the transverse slots, a bolt plate having bevelled projections to intersect said keeper, said plate being slideable in the casing, lateral edge extensions on said plate having lugs, a character carrying knob rotatably mounted in said plate to extend through the longitudinal slot in said casing, a notched disc associated with said knob, a projection on said casing entrable the notch of said disc when said knob is in a predetermined position and the plate drawn in that direction, character carrying knobs rotatable in said casing, and notched discs carried by said knobs rotatable to register with the lugs on said plate.

4. A lock comprising a casing having one or more transverse and longitudinal slots in its face, a keeper engageable selectively in the transverse slots, a knob rotatable and slideable in the longitudinal slot, a bolt plate slideable in said casing in which said knob is revolvable, a notched disc associated with said knob, a pair of knobs revoluble in said casing, notched discs carried by the last named knobs, a lug on said casing adapted to enter the notch in the slideable disc when alined and actuated by the associated knob, projections on said bolt plate adapted to enter the notches in the discs associated with the paired knobs when alined, and means whereby all of said discs may be individually positioned to receive their corresponding lugs and projections and moved to prevent entrance thereof.

5. A lock comprising a casing, a keeper entrable therein, a spring urged bolt slideable in said casing to engage said keeper, a knob for retracting the bolt, means carried by said knob engageable with a casing carried lug to prevent actuation except when in a predetermined position denoted on the knob, a pair of spaced knobs rotatable in the casing,

notched discs carried by said knobs, and lugs on said bolt entrable into the disc notches 10 when in a predetermined position denoted on said spaced knobs.

This specification signed this eighth day of September, 1927.

JOHN RECKER.
